UNITED STATES PATENT OFFICE.

OSCAR WRIGHT, OF PENNANT HILLS, NEAR SYDNEY, NEW SOUTH WALES, AUSTRALIA.

MANUFACTURE OF CHARCOAL.

1,092,418.

Specification of Letters Patent. Patented Apr. 7, 1914.

Application filed August 1, 1912. Serial No. 712,731.

To all whom it may concern:

Be it known that I, OSCAR WRIGHT, a subject of the King of Great Britain and Ireland, residing at Park Road, Pennant Hills, 5 near Sydney, in the State of New South Wales, Australia, have invented certain new and useful Improvements in the Manufacture of Charcoal, of which the following is a specification.

This invention relates to the manufacture of charcoal and has been devised with the object of obtaining a maximum percentage of charcoal of high grade and uniform quality and a minimum percentage of ash.

Heretofore charcoal has been "burned" in covered heaps and in meilers and kilns and in some cases in chambers constructed of iron sheets or plates, these plates being in certain known constructions of said 20 chambers lined with a refractory substance such as firebrick or asbestos millboard. The air vents and smoke vents have been variously arranged in these chambers.

The present invention is a process characterized by the manner of manipulating the drafts in a kiln of certain construction during the burning process therein, whereby the improved effects before mentioned are attained.

The kiln is preferably constructed of metal plates or sheets riveted together and is most conveniently made in rectangular form and used standing vertically. But it may be made of vertical cylindrical or oval 35 form. It need not be closed at the bottom as a sufficiently good closure thereat may be obtained by erecting the kiln on the ground and banking clay or soil around the foot of it. The top or cover plate of the

40 kiln is most conveniently made detachable, so that it may be readily fitted to the body of the kiln and the joint closed by luting with clay or earth after the charge has been inserted. If it is not made detachable, 45 means such as close fitting doors must be provided either in the sides or cover plate of the kiln to facilitate insertion of the charge and effectual closing of the kiln. The top or cover plate is fitted with one or

50 several apertures each fitted with a slide plate or grated damper or other valve arrangements by means of which the area of the aperture or apertures may be varied at will, and it may be fitted with baffles internally for subdividing the internal drafts.

The shell plates of the kiln may be and

are preferably insulated with asbestos millboard, fibro-cement sheeting, or like refractory material to prevent loss of heat during the burning process.

Figure 1 is a broken sectional elevation of a charcoal burning chamber according to my invention, and Fig. 2 a top plan thereof.

In operation, the lid or cover A is removed and the chamber packed with fagots in the usual manner known to charcoal burners and the charge lighted through the bottom doors B, which done, these doors are closed tightly. The cover A is then set in place and luted at C with clay, but the luting may be omitted if the joint is reasonably tight.

The cover A as shown has vents D and E which open upward directly to the atmosphere and which are provided with closures 75 so that the vents can be controlled as desired during the burning of the charge.

The fire having been started at the bottom of the charge, as described, the combustion proceeds gradually from the bottom to 20 the top of the charge. And since the only openings for ingress of fresh air and egress of products of combustion are in the top of the kiln the entering air must flow downward through the charge to reach the zone 25 of combustion, while the products of combustion must pass upward through the unburned part of the charge before finding exit from the chamber. The control of the fire is in large measure automatic, since, if the combustion becomes intense, the upward flowing mass of gases passing outward through the top opening or openings repels the inflow of fresh air, and the fire is automatically checked. When the fire is 95 checked beyond a certain point, the fresh air finds opportunity to enter downward notwithstanding the resistance of the outflowing gases and so a balance is maintained between the outgoing air and consumed gases 100 and the incoming fresh air. However, by reason of various irregularities, such, for example, as variations in the character of the wood, the burning does not always tend to proceed regularly throughout the length 105 and breadth of the combustion zone, so that it is necessary to watch the drafts and manipulate the vent closures from time to time to influence the direction of the combustion and secure its even progress from the bottom of the charge upward. Irregularity of

110 the burning can be detected by comparing

the temperatures at different points on the shell of the kiln.

The area of the top opening or openings can be made such in relation to the capacity of the kiln that the amount of fresh air entering, under the automatic control referred to, suffices only for the distillation of the wood, the entrance of the fresh air into the lower zones of converted wood so as to effect its destruction, being avoided. This desired rate of intensity of the combustion is marked by a certain temperature in the walls of the kiln, and by observing the temperatures and controlling the areas of the vent openings by means of the closures the proper temperature can be maintained and a satisfactory product secured with a minimum of waste.

As has been stated, the cover or top of the kiln may be provided with one vent or with several, this being determined by the form, capacity, or other characteristics of the kiln. When only one vent is provided the incoming air and outgoing gases must both pass through it, and obviously this inflow and outflow through the same opening may occur, too, when several vents are provided; in either case there is provision at the top of the kiln for admission of air and exit of gases in such manner that both traverse practically all parts of the raw wood lying above the charcoal, a natural circulation being set up which promotes a uniform progress of combustion throughout the length and breadth of the charge.

Waste of heat by radiation is minimized by providing the kiln with a lining E' of fibro cement, asbestos board, or like refractory material. F are baffles, the use of which is optional.

Heretofore the uniform practice of burning charcoal whether in pits, meilers or built up ovens, was to admit air for combustion at the bottom and sides of the heap and to allow the gases to pass out at the top. Such a process inevitably led to one result; charcoal was produced but it was produced under conditions which insured the imme-

diate destruction of a certain amount of it and consequent loss. This will be understood when it is remembered that in the upward burning of the charge the hottest portion of the fire is always below. When air enters and comes into contact first with the glowing wood, it consumes some of the charcoal already formed and produces ash and carbonic acid gas, the gas being a loss and the ash a waste. In the case of my invention the air is brought into contact with the distilling wood only and kept out of contact with the carbonized wood, there being no loss of carbonized wood and the distilling process being facilitated.

What I claim as my invention and desire to secure by Letters Patent is:—

1. The herein described process of manufacture of charcoal which consist in inclosing a charge of wood in a chamber, lighting the charge at the bottom thereof, admitting air to and releasing gases of combustion from the charge only at the top thereof, and controlling the rate at which the air is thus admitted and the gases of combustion thus discharged in such manner that the combustion proceeds evenly from bottom to top of the charge while the indraft passes downwardly through all parts of the unburned portion of the charge and the gases of combustion pass upwardly through the same.

2. The herein described process of manufacture of charcoal which consists in inclosing a charge of wood in a chamber having a vent or vents in its top, lighting the charge at the bottom thereof, and admitting air to and releasing gases of combustion from the charge only at the top thereof by natural circulation of the air and gases in and out, respectively, through the said top vent or vents.

In testimony whereof I have affixed my signature in presence of two witnesses.

OSCAR WRIGHT.
